CLAIM

The ornamental design for an airway position support device, as shown and described.

DESCRIPTION

FIG. 1 is an upper perspective view of the airway position support device showing our new design;

FIG. 2 is a right elevation view of the device;

FIG. 3 is a left elevation view of the device, the opposite side of that shown in FIG. 2;

FIG. 4 is a top plan view of the device;

FIG. 5 is a bottom plan view of the device;

FIG. 6 is a front elevation view of the device;

FIG. 7 is a rear elevation view of the device, the opposite side of that shown in FIG. 6; and,

FIG. 8 is a side perspective view of the device, shown in condition of use.

The broken lines showing a human figure in FIG. 8 illustrates environmental structure and forms no part of the claimed design.
